UNITED STATES PATENT OFFICE

JOHN H. DOMKEE, OF NEW HAVEN, CONNECTICUT, ASSIGNOR TO THE WIRE NOVELTY MANUFACTURING COMPANY, OF WEST HAVEN, CONNECTICUT, A CORPORATION OF CONNECTICUT

PRONG BUCKLE

Application filed July 17, 1930. Serial No. 468,567.

This invention relates to prong buckles employed mounted upon one length of strap to be adjustably secured to another length of strap threaded within the buckle and penetrated by the prongs. In this type of buckle the points of the prongs, having penetrated the strap, remain exposed and are thus liable to scratch the hand adjusting the strap and to catch and tear fabrics with which they come in contact. The applicant is aware that improvements to obviate this condition have been made by providing recessed or bent portions of the buckle frame for the reception of the points of the prongs which are either swung or longitudinally advanced therein for protection. Also, in assembling the members of this type of buckle, it is sometimes considered expedient to so jam the pivotal bearings that the points of the prongs are made to snugly lie more or less fixedly against the buckle frame to prevent entanglement of buckle units during the finishing process, but, when the buckles are thus delivered to the trade, difficulty is experienced in mounting the buckles on straps thereby connected because of the resistance against the relative pivotal movement of the buckle members. It is the intention therefore of this invention to not only provide a novel means for the protection of the points of the prongs of a prong buckle, but also to include within that protection a holding means of such efficiency as to hold the points of the prongs protectingly not only during the finishing process but also when in use even though the buckle members are loosely assembled at their pivotal bearings. With the above in mind the objects of the invention are to provide a prong buckle with a novel means for protecting the points of the prongs; to provide such protecting means with means for holding the points of the prongs close against the buckle frame; and to provide a pivotal assembly of the buckle members with a relative movement along their pivotal axis to laterally present the points of the prongs and the combined protecting and holding means, one to the other, and also for their separation when desired. With these and other objects in view as may become apparent from the within dis-

closures, the invention consists not only of the particular form herein pointed out and illustrated in the drawings, but readily admits of certain modifications within the scope of what hereinafter may be claimed, therefore the character of the improvement may be best understood by reference to one illustrative device embodying the invention and illustrated by the accompanying drawings in which the Figure 1 is a front elevation of a 55 prong buckle illustrating the prongs protectingly held; the Figure 2 is a similar elevation but illustrating the buckle members relatively shifted laterally and the prongs free from their protecting holding means; the 60 Figure 3 is a side elevation of the closed prong buckle, the open position of a member being illustrated in dotted lines; and the Figure 4 is a cross-section of the buckle frame on the line "4—4" of the Figure 1, the section 65 being in perspective.

Referring more particularly to the drawings the buckle is illustrated as being made of wire and in two members of which one is herein referred to as the buckle frame 1, and 70 the other as the prong member 2. So far as the members 1 and 2, pivotally assembled in a common plane and relatively movable out of said plane, resemble the usual buckle structure no claim of novelty is herein made; for the pivotal assembly of the frame and prong members 1 and 2 in a common plane for relative movement out of said plane, the flattened section 3 of the frame member 1 parallel to the pivotal axis 4, 75 and the prongs 5 and 6 provided by the prong member 2 and having the pointed ends 7 and 8, respectively, intersectingly engaging the flattened section 3, are all old in the art, the novelty herein disclosed consisting of the peculiar formations with which the flattened section 3 is provided, and the pivotal assembling of the members 1 and 2 so as to permit a relative lateral movement as between the members 1 and 2 along their 80 pivotal axis and a consequent shifting of the points 7 and 8 of the prongs 5 and 6 along the flattened section 3. Each of the formations provided by the section 3 parallel with the pivotal axis 4 is made by 85 90 95 100

cutting an L-shaped incision in the flattened section 3, upwardly forming the metal within the incision and downwardly depressing the metal just outside of the incision and 5 along the edge of the flattened section 3 to provide the off-set housing 9 and the adjacent depressed portion 10. In forming the housing 9 a slight downwardly extending projection 11 is provided by the housing 9 10 to form the restricted entrance 12 to the housing 9 to slightly retard the passing therethrough of the prong points 7 and 8.

In use, the prong buckle is mounted in the usual way upon a strap (not illustrated) 15 fixedly looped upon a bar of the prong member 2. The connecting strap (not illustrated) is threaded in the usual manner into the frame member 1 while the buckle members 1 and 2 are relatively swung to an 20 open condition illustrated in dotted lines by the Figure 3, the connecting strap being penetrated by the points 7 and 8 of the prongs 5 and 6 upon the closing of the buckle members so that the prong points 7 and 8 are 25 exposed in the usual manner to engage against the section 3. The improvement permits the buckle members 1 and 2 then to be relatively moved laterally along their pivotal axis 4 and out of alignment, one with 30 the other, as illustrated by the Figure 2, so that the exposed prong points 7 and 8 are each in the position, as regards the formations of the housing 9 and the depression 10, to be laterally presented to the restricted entrance 12 and laterally moved into the protecting and holding means by the relative 35 return movements of the buckle members 1 and 2 to aligned positions illustrated by the Figure 1 wherein each of the prong points 40 7 and 8 are lodged within and beyond the restricted entrance 12 and between the formations 9 and 10, the prongs 5 and 6 thus being locked, with their points 7 and 8 within in the housing 9, against movement along 45 or out of the plane of the closed buckle. It is evident that this locked condition of the prongs 5 and 6 can be had regardless of the mounting and threading of the strap lengths, so that included in the automatic 50 operations of manufacture the members 1 and 2 may be locked in readiness for the finishing process of the buckle surfaces and for packing without fear of unit entanglement.

I claim:

55 1. A prong buckle having frame and prong members pivotally assembled in a common plane, said pivotal assembly being loose enough to provide relative movements along their pivotal axes and also out of said plane; 60 a flattened section provided by, and in the plane of, the frame and parallel to said axes; prongs provided by the prong member to intersectingly engage the flattened section; and housings provided by and extending 65 along the flattened section, each housing

being formed by making an L-shaped incision in the flattened section and off-setting the metal therein sufficiently out of the plane of said section to provide the housing with openings above, and facing one end and an 70 edge of, the flattened section to admit the end of a prong advanced laterally by the relative axial movement of the buckle members.

2. A prong buckle having frame and prong members pivotally assembled in a common 75 plane, said pivotal assembly being loose enough to provide relative movements along their pivotal axes and also out of said plane; a flattened section provided by and in the plane of the frame and parallel to said axes; 80 prongs provided by the prong member to intersectingly engage the flattened section; and housings provided by and extending along the flattened section, each housing being formed by making an L-shaped incision 85 in the flattened section and off-setting the metal therein in one direction out of the plane of the said section and depressing the metal around the incision in the opposite direction to provide the housing with openings facing 90 one end and an edge of the said section to admit the end of a prong advanced laterally by the relative axial movement of the buckle members.

3. A prong buckle having frame and prong 95 members pivotally assembled in a common plane, said pivotal assembly being loose enough to provide relative movements along their pivotal axes and also out of said plane, a flattened section provided by and in the plane of the frame and parallel to said axes; 100 prongs provided by the prong member to intersectingly engage the flattened section; and prong protecting and holding means provided by and extending along the flattened section and comprising L-shaped incisions in 105 said section, the metal therein off-set in one direction out of the plane of said section and the metal around the incisions depressed in the opposite direction, the off-set metal portions each having an inwardly extending projection, each L-shaped formation thus providing a housing with a restricted end opening and an opening facing an edge of the flattened section to admit and to hold the end 110 of a prong advanced laterally and urged through the restricted opening by the relative axial movement of the buckle members.

4. A prong buckle having a wire frame and a wire prong member pivotally assembled in 115 a common plane, said pivotal assembly being loose enough to provide relative movements along their pivotal axes and also out of said plane; a flattened section parallel to said axes and provided by the wire frame; prongs provided by the prong member to intersectingly engage the flattened section, and housings provided by the flattened section, each housing having an opening to admit the end of a 120 prong advanced laterally by the relative axial 125

movements of the frame and prong member.

5. A prong buckle having a wire frame and a wire prong member pivotally assembled in a common plane, said pivotal assembly being loose enough to provide relative movements along their pivotal axes and also out of said plane; a flattened section provided by and in the plane of the frame and parallel to said axes; prongs provided by the prong member 10 to intersectingly engage the flattened section; and housings provided by the flattened section, each housing having an opening to admit the end of a prong advanced laterally by the relative axial movements of the frame and 15 prong member.
